(21) Appl. No.: **29/299,450**

(57) **CLAIM**

(22) Filed: **Dec. 27, 2007**

The ornamental design for a rotor for an internal combustion engine, as shown and described.

(30) **Foreign Application Priority Data**

Jun. 29, 2007 (JP) 2007-017455

DESCRIPTION

(51) **LOC (9) Cl.** 15-01

FIG. 1 is a front perspective view of a rotor for an internal combustion engine showing my new design;

(52) **U.S. Cl.** D15/5

FIG. 2 is a rear perspective view thereof;

(58) **Field of Classification Search** D15/1,

D15/3, 5; 55/337; 123/41.67, 198 E; 418/91

See application file for complete search history.

FIG. 3 is a front view thereof;

(56) **References Cited**

FIG. 4 is a rear view thereof;
